UNITED STATES PATENT OFFICE

138,121

DESIGN FOR A BOX OR SIMILAR ARTICLE

Ladislas Medgyes, New York, N. Y., assignor to Helena Rubinstein, Inc., New York, N. Y., a corporation of New York

Application February 15, 1944, Serial No. 112,596

Term of patent 7 years

(Cl. D58—12)

To all whom it may concern:

Be it known that I, Ladislas Medgyes, a citizen of Hungary and residing in New York city, New York, have invented a new, original, and ornamental Design for a Box or Similar Article, of which the following is a specification, reference being had to the accompanying drawing, forming part thereof.

The figure is a perspective view of the box or similar article showing my new design.

The dominant features of my design reside in the portions shown in full lines.

I claim:

The ornamental design for a box or similar article, as shown and described.

LADISLAS MEDGYES.
